UNITED STATES PATENT OFFICE.

GEORGE F. CARTER, OF ORANGE, NEW JERSEY.

MUFF-BLOCK.

SPECIFICATION forming part of Letters Patent No. 406,260, dated July 2, 1889.

Application filed September 20, 1888. Serial No. 285,840. (No model.)

To all whom it may concern:

Be it known that I, GEORGE F. CARTER, a subject of the Queen of Great Britain, residing at Orange, in the county of Essex and State 5 of New Jersey, have invented certain new and useful Improvements in Muff-Blocks; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 The object of my invention is to facilitate and expedite the operation of stretching and shaping the muff-skin on the muff-block, to secure a more uniform shape and stretching of the skin, simplify the operation, and lessen 20 the cost of manufacture.

The invention consists in constructing the muff-block in sections in a special manner, the mode and means employed to tighten and shape the skin on the block, and the arrangements and combinations of parts, as will 25 be hereinafter more fully set forth and embodied in the clauses of the claim.

In the accompanying drawings, in which like 30 letters of reference indicate corresponding parts in each of the several figures, Figure 1 is an end view of a muff-block embodying my improvement. Fig. 2 is a central transverse section of the block, showing the sectional divisions of the main block; and Fig. 35 3 is a longitudinal section through line x of Fig. 1, showing more completely the end pieces and the mode of connecting them to the main block.

In said drawings, A represents a complete 40 muff-block formed, as shown in Fig. 2, of five tapering segmental sections a a and a tapering regulating or adjusting section b.

c is a tapering cylinder or truncated cone adapted to enter the central portion of said 45 block and firmly bind the muff-skin and blocks together in a complete shape designed by the blocks.

d d are adjustable wrist-blocks with tenons d' d', fitting into sockets c' c' in cylinders c. 50 The operation is as follows: The muff-

leather is first cut of a little shorter length than the circumference of the block to be used, so as to allow of its being stretched when on the block. The ends of the skin are then stitched together, forming a bag. Two 55 or three of the segmental pieces of the block are then placed on the inside of the bag, after it has been thoroughly moistened, at equal distances from the sides. These segmental pieces, with the leather, are then stood upon 60 their ends, and the remaining segmental pieces are then put in their proper position, and then the adjusting-section is inserted, thus holding the sections of the block loosely 65 together. The small end of the central tapering cylinder is then placed in the larger hole of the cylindrical opening of the block and is at once driven in until the ends of the cylinder are flush, or nearly so, with the ends of 70 the block. This action causes the segmental 75 sections and the adjusting-section together to form the complete block, and the muff-leather is drawn very tight over the surface of the block. The wrist-blocks are then inserted in the ends of the block, and the outer loose 80 edges of the leather are securely fastened to the outer periphery of the wrist-blocks. The portion of the leather between the end of the main block and the end of the wrist-block is then drawn tightly by a cord into the angle 85 formed at the junction of the wrist-block and the main block. The block with the leather is then set away to dry. When thoroughly dry, the nails or fastenings are first removed from the wrist-blocks and the wrist-blocks 90 then removed. The tapering cylinder is then driven out, the sections are loosened, and the leather slipped off in the shape of the muff-block.

Having thus described my invention, what I 95 claim as new is—

1. A muff-block made substantially as herein described, consisting of a series of cylindrical sections and a smaller adjusting-section b, the inner sides of said sections forming a central tapering cylindrical opening through the block, and a tapering cylinder adapted to fit said central opening to bind a muff-skin tightly and uniformly on said block throughout its length, as set forth. 100

2. A muff - block made substantially as herein described, consisting of a series of cylindrical sections, and a smaller adjusting-section *b*, the inner sides of said sections forming a central tapering cylindrical opening through the block, a tapering cylinder adapted to fit said central opening to bind a muff-skin tightly and uniformly on said block, and adjustable wrist - blocks with tenons to enter

sockets in the ends of said tapering cylinder, to as set forth.

In testimony that I claim the foregoing I have hereunto set my hand this 17th day of August, 1888.

GEO. F. CARTER.
